UNITED STATES PATENT OFFICE

117,087

DESIGN FOR A TEXTILE FABRIC

Hugh J. Carragher and Thurston B. Wilson,
Brooklyn, Conn., assignors to Powdrell and Alexander, Inc., Danielson, Conn., a corporation of Massachusetts

Application August 17, 1939, Serial No. 86,753

Term of patent 3½ years

To all whom it may concern:

Be it known that Hugh J. Carragher and Thurston B. Wilson, citizens of the United States, residing in Brooklyn, in the county of Windham and State of Connecticut, have invented a new, original, and ornamental Design for a Textile Fabric of which the following is a specification, reference being had to the accompanying drawing, forming part thereof.

The figure is a plan view of a textile fabric showing our new design.

We claim:

The ornamental design for a textile fabric, as shown.

HUGH J. CARRAGHER.
THURSTON B. WILSON,
